GEORGE S. CRAWFORD, OF CHICAGO, ILLINOIS, ASSIGNOR TO SOPHIE L. WOODS, OF CHICAGO, ILLINOIS

SIDE BEARING

Application filed January 21, 1927. Serial No. 162,438.

This invention relates to certain novel and useful improvements in anti-friction bearings, more especially adapted for use as side bearings for railway cars and consists of the 5 matters hereinafter described and more particularly pointed out in the appended claims.

The invention as shown herein and in its preferred embodiment is a side bearing to be applied to the body bolster, as distinguished 10 from the truck bolster, of a railway car and its novel features of construction render its use of particular advantage when thus applied.

The object of the invention is to provide 15 a bearing of the kind of simple and economical construction, in which the anti-friction roller, suspended from the casing, is supported and centered by an improved resilient or spring-controlled mechanism in which the 20 work of the resilient member or spring is accomplished with a minimum of expansion and contraction thereof.

The many advantages of my invention will appear more fully as I proceed with my specification.

In the drawings:

Figure 1 is a view representing the improved side bearing in top plan elevation.

Figure 2 is a view representing the improved bearing partly in side elevation and partly in longitudinal central section.

Figure 3 is a view representing a transverse vertical section through the bearing in a plane indicated by the line 3-3 of Figure 2.

Figure 4 is a fragmentary side elevation shown partially in longitudinal central section showing the roller and the other parts as when the roller is off center.

Referring now to that embodiment of the 40 invention illustrated in the drawings, and more particularly in Figures 1 to 3 thereof;— 10 indicates a casing adapted to be secured to the bottom side of a body bolster 11 in any usual or familiar manner. As shown, the 45 body bolster is inclined at an angle to the

horizontal and the base plate 12 of the casing has its top face correspondingly inclined at an angle to the horizontal (transversely of the casing) for attachment to said body bolster. Projecting ears or extensions 13, 13 50 at the ends of the base plate are provided with bolt holes for securing the casing to the bolster in the manner described.

The casing is preferably made hollow with a bottom wall 14 and with integral vertical 55 side members 15, 15 and end members 16, 16. Said bottom wall 14 presents a bearing surface 17 on its bottom side against which an anti-friction roller 18 is designed to roll. The vertical side and end members 15 and 60 16 project somewhat below the bearing way or surface 17—the side walls 15 providing side ways 15^a, 15^a to guide the ends 19, 19 of the roller and the end walls 16 providing stops 16^a, which are curved substantially to 65 the curvature of the cylindrical surface of the roller and merge into the bearing surface 17 on the bottom wall of the casing.

Extending transversely of the casing midway between its ends is a boss or rib 20, 70 which is integral with and extends upwardly from the bottom wall 14. In said rib is a transverse recess 21, which is enlarged at its middle to receive a coiled spring 22. A stud 23 at the bottom of the recess 21 centers the 75 spring 22 at its lower end. Its upper end engages a downwardly extending stud 24, on a transverse bar 25. Said bar fits loosely in the top of the recess 21 (see Figure 1) and is vertically movable therein.

26 indicates a U-bar the legs 26^a of which embrace the sides of the casing and the bottom or base member 26^b of which is formed to provide a shaft which extends loosely through a central bearing aperture 19^a in the 85 anti-friction roller. The legs of the U-bar are formed at their upper ends with elongated slots or eyes 27 in which engage the ends of the transverse bar 25. Shoulders 28 at the ends of the bar 25 beyond the legs 90

of the U-bar 26 lock the bar in its engagement within the eyes 27 of said legs. Thus the roller is connected to the casing by an oscillatable member, namely the U-bar 26; a vertically movable head member above the bearing surface 17 of the casing, namely the transverse bar 25; and a vertically acting resilient member or spring interposed between the head member and the casing, namely the spring 22.

It will be manifest from the foregoing description that the coiled spring will act to force the U-bar upwardly and by it to draw the roller into contact with the wear or bearing surface 17 on the bottom wall 14 of the casing,—this because the coiled spring 22, expanding between the bottom of the recess 21 and the bar 25, will cause said bar to engage in the tops of the eyes 27 of the U-bar and force said U-bar upwardly. When the roller 18, by reason of its engagement against a bearing plate on the truck bolster is caused to roll along the bearing surface 17 towards one or the other end of the casing, this movement will act through the U-bar 26 and the transverse bar 25 to compress the spring 22 in proportion to the distance the roller moves beyond its normal middle position. The base member of the U-bar follows the roller in its movement as shown in Figure 4 while its upper ends remain substantially stationary,—the U-bar as a whole being pivoted by its eyes 27 on the transverse bar 25. The U-bar thus assumes positions corresponding to the hypothenuse of a right angle triangle, whose base represents the distance the roller is displaced from the center and whose altitude represents the line of action of the spring 22. Taking this to represent the triangle of forces acting upon the roller 18, it will be seen that the base of the triangle represents the force tending to return the roller to its normal central position.

Upon the release of the roller by the bottom bearing plate, the expansion of the spring will act to draw the U-bar 26 upwardly and the horizontal component of the pull exerted through the U-bar will act to return the roller to its central position.

It will be noted that in this operation the spring will only be compressed through a distance measured on and in proportion to the vertical component of the aforesaid triangle of forces acting on the roller. This greatly reduces the movement of the spring in the operation of the device and tends to promote and prolong the life of its elastic efficiency.

As the space allowed for a side bearing is generally limited and particularly with a bolster having an inclined bottom plate for the attachment of the side bearing as herein illustrated, said bolster plate 11 is preferably provided with a slot 11^a formed and located to permit the projection therethrough of the upper ends of the U-bar. Such slot must be

made of such width as to permit the free swinging movement of said U-bar as heretofore explained.

In order to prevent carelessness in the punching by the car builder of the necessary hole or slot 11^a in the bolster plate 11 from interfering with the proper operation of the bearing, it is preferred to extend the transverse rib 20 in which the spring 22 and transverse bar 28 are located, somewhat above the level of the top plane of the bearing member 10, as shown in Figures 2 and 3. This will prevent the application of the bearing to a bolster plate until the slot 11^a therein has been properly cut and positioned.

While in describing the invention I referred to several details of mechanical construction and arrangement as embodied in the preferred form of the construction, particularly when applied to a body bolster, it will be understood that the invention is not limited thereby nor to that application (it also being capable of use with a truck bolster) except as may be pointed out in the appended claims.

I claim as my invention:

1. In a side bearing, in combination with a bearing member presenting a bearing surface on one side and being constructed for attachment to a bolster on its other side, a transversely disposed roller engaged with said bearing surface, a transversely disposed vertically movable bar on the bolster side of said bearing member, a U-bar embracing the sides of said bearing member and pivotally connected to said transverse bar, said U-bar having a bottom member engaged with said roller and an expansion coiled spring acting in a vertical direction only interposed between said bar and said bearing member.

2. In a side bearing, in combination with a bearing member presenting a bearing surface on one side and being constructed for attachment to a bolster on its other side whereon it is provided with a transverse recess enlarged at its middle to provide a seat for a coiled spring, a transversely disposed roller engaged with said bearing surface, a transverse bar movable vertically in the transverse recess in said bearing member, a U-bar embracing said bearing member and pivotally engaged with said transverse bar, said U-bar having a bottom member engaged in said roller, and an expansion coiled spring acting in a vertical direction only disposed in said recess and engaged with said transverse bar.

3. In a side bearing, in combination with a bearing member presenting a bearing surface on one side with lateral guideways at the sides and stop members at the ends thereof and being constructed for attachment to a bolster on its other side whereon it is provided with a transverse recess enlarged at its middle to provide a seat for a coiled spring, a transverse roller engaged with said bearing sur-

face, a transverse bar movable vertically in the transverse recess in said bearing member, a U-bar embracing said bearing member and pivotally engaged with said transverse bar, said U-bar having a bottom member engaged in said roller, and an expansion coiled spring acting in a vertical direction only disposed in said recess and engaged with said transverse bar.

5 In testimony that I claim the foregoing as my invention, I affix my signature this 13th day of January, A. D. 1927.

10 GEORGE S. CRAWFORD.
